(57) **CLAIM**

The ornamental design for an adapter housing for a peristaltic pump, as shown and described.

DESCRIPTION

FIG. 1 is a front top perspective view of an adapter housing for a peristaltic pump according to an embodiment of the invention.

FIG. 2 is a rear top perspective view of the adapter housing of FIG. 1.

FIG. 3 is a front bottom perspective view of the adapter housing of FIG. 1.

FIG. 4 is a top view of the adapter housing of FIG. 1.

FIG. 5 is a bottom view of the adapter housing of FIG. 1.

FIG. 6 is a right side view of the adapter housing of FIG. 1.

FIG. 7 is a left side view of the adapter housing of FIG. 1.

FIG. 8 is a front view of the adapter housing of FIG. 1; and,

FIG. 9 is a rear view of the adapter housing of FIG. 1.

The portions of the drawings appearing in broken lines are for environment only and do not form a part of the claimed design.

1 Claim, 8 Drawing Sheets
